UNITED STATES PATENT OFFICE.

LEE S. CHADWICK, OF CLEVELAND, OHIO, ASSIGNOR TO THE CLEVELAND METAL PRODUCTS COMPANY, OF CLEVELAND, OHIO, A CORPORATION OF OHIO.

OIL BURNER.

Application filed April 29, 1920. Serial No. 377,467.

To all whom it may concern:

Be it known that I, LEE S. CHADWICK, a citizen of the United States, residing at Cleveland, in the county of Cuyahoga and State of Ohio, have invented a certain new and useful Improvement in Oil Burners, of which the following is a full, clear, and exact description, reference being had to the accompanying drawings.

10 This invention relates to an improved indicator and wick stop for use with oil burners.

In oil burners of the class wherewith my improvements are adapted for use, the wicks 15 have a normal range of movement between what may be termed "high" position—the highest at which the wick should be turned in the normal use of the burner—and what may be termed "out" position—the position 20 to which the wick may be turned to extinguish the flame. Between these are the usual "medium" and "low" positions. However, there is an abnormally high position to which the wick may be turned to facilitate 25 lighting.

It is the primary object of my invention to provide means serving ordinarily to restrict the wick to its normal range of movement, but which may be readily manipulated 30 to render it ineffective as a limiting means, permitting the wick to be elevated beyond "high" position to allow of easy lighting.

A further object is to combine with such means, an indicator for designating the various positions of the wick; and further objects are to provide an improved construction of an adjustable connection between the wick operating spindle and the indicator and stop, whereby the relation between the 40 wick, and the indicator and stop may be readily altered to compensate for wick consumption, such connection being simple in construction and economical of manufacture, yet highly efficient, strong and durable 45 and convenient of adjustment.

An embodiment of my improvements is illustrated in the accompanying drawing and while the same constitutes my present preferred construction, it should be regarded 50 as an example only for it may be changed and modified in many respects without departing from the spirit or exceeding the scope of my invention.

In the drawings, Fig. 1 is a side elevation 55 of an oil burner equipped with my improved

indicator and stop, parts of the burner being broken away to reveal the wick and certain structural details; Fig. 2 is a sectional view on the line 2—2 of Fig. 1; Fig. 3 is a section at right angles to Fig. 2 on 60 the correspondingly numbered line of said figure; Fig. 4 is a sectional development on the line 4—4 of Fig. 2; and Fig. 5 shows the elements of the latch, through which the spindle and indicator are adjustably connected, in perspective and in separated condition.

The type of burner wherein I have elected to show my improvements incorporated is comprised of inner and outer wick tubes 1 70 and 2, respectively, that are connected together at their lower ends with a liquid-tight joint so as to enclose between the tubes an annular wick space wherein a wick 3, supported within a carrier 4, is adapted to 75 be raised and lowered by means of a spindle 5 having star wheels or pinions 6 that mesh with perforations 7 of the carrier 4. The spindle 5 projects forwardly and upwardly from the burner through a tubular casing 8 80 and has connected to its outer end beyond said casing a hand wheel 9. The burner derives its supply of oil from a pipe 10 whereon the burner is mounted and wherewith it has communicating connection 85 through a fitting 11, indicated in dotted lines in Fig. 1. All of this is in accordance with long established practice and further description and illustration is therefore deemed unnecessary.

A hat-shaped dial, designated generally by 15, is secured to the tubular casing near its outer end and it comprises a rim portion 16, having its outer edge curled over to the rear, and a crown portion 17, the central 90 part of which is depressed in a frusto-conical shape to provide a cavity 18, the connection between the dial and the casing 8 being made at the center of this frusto-conical portion.

A yoke 20, having apertured front and rear branches 21 and 22, respectively, with an abruptly bent portion between the branches which produces a restricted niche 23, is journaled on the outer end of the tubular casing 8 and the rear branch 22 occupies the cavity 18. 25 is a latch constructed of sheet metal and comprising a central web 26 and side flanges 27. The web 26 is notched upwardly from its lower 110

end for engagement over the tubular casing 8 and its lower extremity is designed to occupy the restricted niche 23 of the yoke 20, the side flanges 27 of the latch being disposed on opposite sides of the branch 21. A retaining washer 28 surrounds the tubular casing 8 immediately to the rear of the latch and it is provided with a lug 29 that is engaged through a slot 30 in the web 26 of the latch. A spring 35 is compressed between the washer and the rear branch of the yoke 20 and serves not only to retain the lug 29 of washer 28 within the slot 30, but also to rock the latch forwardly on the fulcrum provided by the confinement of its lower end within the niche 23 and project the teeth 36 that are formed on the forward edges of the flanges 27 into locking engagement with teeth 37 that are formed at the rear edge of the peripheral flange of hand wheel 9. The flanges 27 are enlarged near their outer ends to provide finger holds 38, and a tongue is thrust out from the web 26 and bent backwardly and then outwardly to form an index pointer 39 which is in very close proximity to the rim portion 16 of the dial when the teeth 36 of the latch are interengaged with those of the hand wheel.

Engagement of the index pointer 39 with the rim portion 16 of the dial prevents withdrawal of the teeth 36 of the latch from those of the hand wheel except when the index pointer is in register with an opening 40 in said rim portion. As will be seen by reference to Fig. 2, the rim portion of the dial has inscribed upon it—reading from left to right—“High”, “Medium”, “Low” and “Out” and associated with the latter is an arrow indicating that to extinguish the flame the index finger should be swung to the limit of its movement in a left hand direction. Movement of the index pointer in the opposite direction beyond “high” position is ordinarily blocked by a stop 42 which, in the present instance, is formed of a tongue of thin, resilient material, such as spring brass, that has one of its ends secured, as by means of a deposit of solder indicated at 43, to the underneath or rear side of the rim portion 16 of the dial and is led therefrom for a distance along said rear side and thence through a slot 44 to a position beyond the front of the dial, the strip of material departing gradually from the plane of said rim portion until it reaches a point where it is bent abruptly toward said portion and is projected through a slot 45 thereof beyond which it is bent laterally to prevent withdrawal of its end through the last mentioned slot. As hereinbefore explained, it is desirable to elevate the wick beyond “high” position when lighting the burner. This may be done by depressing the spring stop 42 and swinging the index pointer beyond said stop after which the

stop may be released; and after the wick has been lighted the index pointer may be returned to its normal range of movement, the spring stop retracting under the action of the index pointer to permit passage of the latter.

I may explain that the reason for locating the opening 40 at the “medium” position is because the wick, when in such position, should be substantially flush with the tops of the wick tubes. As the wick is consumed and makes necessary a readjustment of the wick raising and lowering spindle 5 with respect to the indicator, the index pointer is brought into register with the opening 40 and the latch is pressed rearwardly against the tension of spring 35 to disengage the teeth 36 from those of the hand wheel 9, so that the hand wheel may be rotated to bring the top of the wick flush with the tops of the wick tubes, after which the latch may be released and allowed to interlock with the hand wheel. Now, by turning the hand wheel, the wick may be brought accurately to any of the positions indicated on the dial.

Having thus described my invention, what I claim is:

1. In a burner of the class described, the combination with the wick raising spindle, of opposed members, the first rotatable with the spindle and the second with respect whereto the spindle is rotatable, an element disposed between said members and rotatable on the axis of the spindle, and a device adapted to rock within said element toward and from the first member, the device having parts for interlocking engagement with parts of the first member and a portion for engagement with the second member to prevent withdrawal of its aforesaid parts from those of the first member, the second member being designed to permit separation of the aforesaid parts when the device is in a given position with respect to said second member.

2. In a burner of the class described, the combination with the wick raising spindle, of opposed members, the first rotatable with the spindle and the second with respect whereto the spindle is rotatable, an element disposed between said members and rotatable on the axis of the spindle, a device adapted to rock within said element toward and from the first member, the device having parts for interlocking engagement with parts of the first member and a portion for engagement with the second member to prevent withdrawal of its aforesaid parts from those of the first member, the second member being designed to permit separation of the aforesaid parts when the device is in a given position with respect to said second member, and means tending to rock the device toward the first member.

3. In a burner of the class described, the combination with the wick raising spindle, of a dial with respect to which the spindle is rotatable, a hand wheel secured to the 5 spindle in spaced relation to the dial and having a series of teeth, a yoke rotatable on the axis of the spindle and situated between the dial and hand wheel, a latch arranged to rock toward and from the hand wheel within 10 said yoke, a member for retaining the latch in proper relation to the yoke, means tending to project the latch in a direction to engage a part of the latch with the teeth of the hand wheel, the latch and dial having 15 parts which engage to prevent the withdrawal of the aforesaid part of the latch from the hand wheel, the dial being cut away at a given point to permit the passage of the last mentioned latch part and the 20 withdrawal of the former latch part from cooperation with the hand wheel teeth.

4. In a burner of the class described, the combination with the wick raising spindle, of a dial with respect to which the spindle 25 is rotatable, a hand wheel secured to the spindle, a member having spaced branches that are rotatable upon the axis of the spindle and disposed between the dial and hand wheel, a latch that is adapted to rock with- 30 in said member and having parts for interlocking engagement with parts of the hand wheel, and a spring disposed between the branch of said member that is furthest removed from the hand wheel and the latch 35 and serving to project the latch toward the hand wheel to interengage the aforesaid parts, the latch having a portion arranged to abut the dial and prevent the withdrawal of the latch parts from those of the hand wheel, the dial being cut away at one point to permit the passage of said portion so that the 40 aforesaid parts may be disengaged.

5. In a burner of the class described, the combination with the wick raising spindle, 45 of a dial with respect to which the spindle is rotatable, a hand wheel secured to the spindle and having circumferential teeth directed toward the dial, a member having spaced branches that are rotatable upon the 50 axis of the spindle and disposed between the dial and hand wheel, a latch that is adapted to rock within said member and having parts for cooperation with the teeth of the hand wheel, and a spring disposed between the 55 branch of said member that is furthest removed from the handwheel and the latch and serving to project the latch toward the hand wheel, the latch having a portion arranged to engage the dial thereby to prevent the 60 withdrawal of the aforesaid parts from the teeth of the hand wheel, the dial being cut away at one point to permit the passage of said portion so that the aforesaid parts of the latch may be disconnected from the hand 65 wheel.

6. In a burner of the class described, the combination with the wick raising spindle, of a dial with respect to which the spindle is rotatable, a hand wheel secured to the spindle and having circumferential teeth, a 70 yoke having spaced branches that are rotatable on the axis of the spindle and which is situated between the hand wheel and dial, the yoke having a restricted notch between its branches, a latch having a web and side 75 flanges, the web being notched to straddle the spindle so that the end of the latch may bear within the restricted notch and the side flanges of the latch may be engaged on opposite sides of one of the branches of the yoke, a washer surrounding the spindle and interlocking with the latch to hold it against withdrawal from the spindle, a compression 80 spring interposed between said washer and the other branch of the yoke, the latch having parts interengaging with the teeth of the hand wheel and a portion arranged to engage a part of the dial thereby to prevent withdrawal of the aforesaid parts from the 85 teeth of the hand wheel, the dial having a portion cut away to permit of the passage of said portion and the withdrawal of the aforesaid parts from interengagement with the hand wheel teeth.

7. In a burner of the class described, the combination with the wick raising spindle, of a tubular casing enclosing the spindle, a hand wheel secured to the spindle beyond the end of said casing and having a series 90 of teeth, a dial secured to the casing in spaced relation to the hand wheel, a yoke having apertured branches that are spaced apart and journaled upon the casing between the hand wheel and dial, the yoke having a restricted notch between its branches, a latch comprising 95 a web and right angle side flanges, the web being notched to straddle the casing so that the end of the latch may engage within the restricted notch of the yoke, the side flanges of the latch embracing one branch of 100 the yoke, a retaining washer surrounding the casing and having a part interlocking with a part of the latch to hold the latch against withdrawal from the aforesaid notch, and a spring confined between the washer and the other branch of the yoke and tending to rock the latch toward the hand wheel, the latch having teeth for interengagement with the teeth of the hand wheel and an index pointer projecting from 105 the web of the latch plate toward the dial and arranged to engage a part of the dial to prevent withdrawal of the teeth of the latch from the teeth of the hand wheel, the dial having an opening for the passage of said index pointer to permit disconnection of the latch and hand wheel when the latch is in a given position with respect to the dial.

8. In a burner of the class described, 110

the combination with the wick raising spindle, of a tubular casing enclosing the spindle, a hand wheel secured to the spindle beyond the end of said casing and having
5 a series of teeth, a dial secured to the casing in spaced relation to the hand wheel, a yoke having apertured branches that are spaced apart and journaled upon the casing between the hand wheel and dial, the yoke
10 having a restricted notch between its branches, a latch comprising a web and right angle side flanges, the web being notched to straddle the casing so that the end of the latch may engage within the
15 restricted notch of the yoke, the side flanges of the latch embracing one branch of the yoke, a retaining washer surrounding the casing and having a part interlocking with a part of the latch to hold the latch against
20 withdrawal from the aforesaid notch, a spring confined between the washer and the

other branch of the yoke and tending to rock the latch toward the hand wheel, the latch having teeth for interengagement with the teeth of the hand wheel and an index 25 pointer projecting from the web of the latch plate toward the dial and arranged to engage a part of the dial to prevent withdrawal of the teeth of the latch from the teeth of the hand wheel, the dial having an 30 opening for the passage of said index pointer to permit disconnection of the latch from the hand wheel when the latch is in a given position with respect to the dial, and a movable stop carried by the dial 35 and serving normally to limit the movement of the index pointer in a direction wherein the spindle is turned to elevate the wick.

In testimony whereof, I hereunto affix my signature.

LEE S. CHADWICK.
